UNITED STATES PATENT OFFICE.

HARRY C. BREWSTER, OF SHREVEPORT, LOUISIANA.

DRILLING MACHINE.

Application filed September 19, 1921. Serial No. 501,702.

To all whom it may concern:

Be it known that I, HARRY C. BREWSTER, a citizen of the United States, and resident of Shreveport, in the parish of Caddo and State of Louisiana, have invented certain new and useful Improvements in Drilling Machines, of which the following is a specification.

This invention relates to well drilling machinery and more particularly to a rotary drilling apparatus.

An important object is to provide a well drilling apparatus having a sub or suspended bed arranged beneath the main bed and the rotary table of the machine, the said bed being provided with suitable means for gripping a drill stem or pipe to hold the same against rotation independently of the rotary table.

20 A further object of the invention is to provide a well drilling apparatus of the class described wherein the sub bed is located out of the way of the rotary table and it does not in any way interfere with the operation of the same.

Other objects and advantages of the invention will be apparent during the course of the following description.

In the accompanying drawings, forming a part of this application, and in which like numerals are employed to designate like parts throughout the same,

Figure 1 is a fragmentary plan view of the improved rotary table, the view illustrating the rotary table partly broken away.

Figure 2 is a detail longitudinal vertical sectional view through the apparatus.

Figure 3 is a perspective of a bushing embodied in the invention.

40 Figure 4 is a perspective of a bushing for locking the drill stem to the turn table.

Figure 5 is a perspective of a pair of slips embodied in the invention.

Figure 6 is a vertical transverse sectional view through the apparatus, the view illustrating the drill stem extended through the same.

Figure 7 is a perspective of the sub or suspended bed.

50 Figure 8 is a plan view of the sub bed. In the drawing the numeral 5 generally designates the improved machine which includes spaced parallel skids 6 connected intermediate their ends by a sub bed 7, the said sub bed 7 being provided with laterally projecting flanges 8 which are imbedded

in the upper sides of the skids 6 and secured thereto by bolts 9. With reference to Figure 6 it will be observed that the sides of the sub bed 7 flatly contact with the inner sides of the skids 6 and that the bolts 9 which secure the flanges to the skids also extend through the main bed 11 to firmly anchor the same to the skids.

With reference to Figure 6 it will be observed that the sub bed 7 is provided with a centrally located gradually reduced opening 12 which snugly receives a tapered bushing 13, the said bushing being provided with oppositely arranged longitudinally extended ribs 14 which extend to two oppositely arranged grooves 15 in the side walls of the opening 7 so as to hold the bushing 13 against rotation. The upper end of the bushing 13 is enlarged laterally to provide an annular shoulder 16 which contacts with the top of the sub bed 7 and thereby limits the downward movement of the bed and also reinforces the upper portion of the bushing.

The drill stem or pipe 18 is passed through the bushing 13 and is adapted to be connected to the bushing by means of a pair of semi-circular slips or gripping devices 19 having their inner sides provided with teeth which firmly grip the pipe and thereby hold the same in position. The upper ends of the semi-circular slips 19 are provided with handles 20 by means of which the slips may be removed when desired.

It is thus seen that the drill stem or pipe 18 may be gripped by the slips 19 and thereby held against rotation with relation to the sub bed which as set forth above is entirely independent of the main bed and the turn-table. By providing a means for gripping the drill stem or pipe beneath the turn table, the tongs may be engaged with the upper portion of the drill stem for screwing or unscrewing the same as may be desired.

The under side of the turn-table is as usual provided with an annular series of gear teeth 22 engaged by an operating pinion 23 secured upon one end of a shaft 24. The shaft 24 of course extends from a suitable source of power and rotates the pinion 23 in any desired direction so that the table which is designated by the numeral 26 may be rotated. An annular series of anti-friction elements 28 may be arranged between the turn table 26 and the main bed 11. The main bed 11 is provided with a plurality of inwardly extending arms 30 which extend

into an annular groove 31 in the turn table 26 so that the turn table is held against upward movement and from disengagement with the pinion 23.

5 A collar designated by the numeral 34 and clearly illustrated in Figure 4 may be arranged upon the turn table 26 to form a gripping means for the fluted stem 36.

With reference to the foregoing descrip-

- 10 tion taken in connection with the accompanying drawing it will be seen that sub bed which is suspended beneath the main bed is provided with means for gripping the drill stem independently of the rotary mem-
 15 ber 26 and also independently of the main bed 11. Therefore, when it is desired to screw or unscrew the drill stem it is merely necessary to insert the slips or gripping de-
 20 vices 19 into the bushing 13 and thereby connect the lower portion of the stem to the sub bed. The tongs may now be engaged with the upper portion of the stem in the usual manner and the rotation of the turn table will result in the rotation of the upper
 25 portion of the drill stem.

Having thus described my invention, what I claim is:—

1. A drilling machine comprising skids, a sub-bed having attaching members im-
 30 bedded in said skids, a main bed arranged above the sub-bed and having gripping de-
 35 vices.
2. A drilling machine comprising skids, a sub-bed having attaching members im-
 35 bedded in said skids, a main bed arranged above the sub-bed and having gripping de-
 40 vices, and gripping devices associated with the sub-bed and having means for gripping the drill stem independently of the main bed.
- 40 3. A drilling machine comprising skids, a sub-bed having attaching members im-
 35 bedded in said skids, a main bed arranged upon and connected to the sub-bed, gripping de-
 45 vices associated with the sub-bed, and a turn table mounted on said main bed and having gripping members, said first and second named gripping members being independent of each other.

4. A drilling machine comprising a main

bed, a sub bed arranged beneath said main 50 bed and having laterally directed flanges, a pair of skids having fastening devices ex-
 55 tends through said flanges and said main bed whereby to connect the main bed and sub bed to the skids, and a gripping device carried by said sub bed and having means for gripping the drill stem independently of the main bed.

5. A drilling machine comprising a main 60 bed, a sub bed arranged beneath said main bed and having laterally directed flanges, a pair of skids having fastening devices ex-
 65 tends through said flanges and said main bed whereby to connect the main bed and sub bed to the skids, a gripping device car-
 70 ried by said sub bed and having means for gripping the drill stem independently of the main bed, and a turn table rotatably mount-
 75 ed upon said main bed.

6. A rotary drilling machine comprising 70 skids, a sub bed confined between said skids and having laterally directed flanges im-
 75 bedded in said skids, the upper surface of said sub bed being flush with the upper sur-
 80 face of said skids, a main bed mounted upon said sub bed and said skids, said sub bed being provided with oppositely arranged grooves, a bushing extended through said sub bed and having ribs received in said grooves, and slips extending into said bush-
 85 ing and having teeth engaging the drill stem.

7. A rotary drilling machine comprising 85 skids, a sub bed confined between said skids and having laterally directed flanges im-
 90 bedded in said skids, the upper surface of said sub bed being flush with the upper sur-
 95 face of said skids, a main bed mounted upon said sub bed and said skids, said sub bed being provided with oppositely arranged grooves, a bushing extended through said sub bed and having ribs received in said grooves, slips extending into said bushing and having teeth engaging the drill stem, and a turn table rotatably mounted upon said main bed.

HARRY C. BREWSTER.
